UNITED STATES PATENT OFFICE.

WILLIAM A. DUNLAP, OF PITTSBURG, PENNSYLVANIA.

MINER'S LAMP.

SPECIFICATION forming part of Letters Patent No. 643,112, dated February 13, 1900.

Application filed September 13, 1898. Serial No. 690,835. (No model.)

To all whom it may concern:

Be it known that I, WILLIAM A. DUNLAP, a citizen of the United States, residing at Pittsburgh, in the county of Allegheny and State of Pennsylvania, have invented or discovered certain new and useful Improvements in Miners' Lamps, of which improvements the following is a specification.

The invention described herein relates to certain improvements in miners' lamps, and has for its object the addition to such lamps of a shield or protecting-plate adapted to prevent the flame from coming into contact with the miner's hat.

The invention is hereinafter more fully described and claimed.

In the accompanying drawings, forming a part of this specification, Figure 1 is a top plan view of a miner's lamp having my improvement applied thereto. Fig. 2 is a view partly in side elevation and partly in section, the plane of section being indicated by the line II II, Fig. 1; and Fig. 3 is a front elevation of the lamp.

The lamp as regards its body 1 and spout 2, lid 3, and attaching-hook 4 is constructed in the usual or any suitable manner. The shield is preferably made of metal and circular in outline, as shown. A hole is formed in this disk or shield for the reception of the spout and is so located that when slipped to the proper position on the spout the lower edge of the disk will be on a level with the bottom of the lamp. The disk is provided along the

edges of the hole with oppositely-projecting flanges 6, adapted to bear on the upper and lower sides of the spout. It is preferred to form these flanges or bearing-strips by cutting the hole in the disk of a diameter less than that of the spout. The opposite edges of the metal are then notched or cut for a distance equal to the desired width of the flanges. The metal adjacent to the hole in one side of the notches is then bent outwardly in one direction and that on the opposite side of the notches in the opposite direction. These flanges can be shaped to fit the spout tightly and prevent the disk from being shifted to an angular position with relation to the spout. A brace having a curved portion 7, adapted to fit the body of the can-legs 8 with outturned ends, is riveted to the body above the spout and to the disk, thereby firmly securing the latter in position.

I claim herein as my invention—
A miner's lamp in combination with a disk or shield having an opening for the reception of the spout and provided with oppositely-projecting bearing-pieces or flanges, and a brace secured to the lamp and the disk, substantially as set forth.

In testimony whereof I have hereunto set my hand.

WILLIAM A. DUNLAP.
